UNITED STATES PATENT OFFICE.

JOHN P. GLASHOWER, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

LAP-MACHINE.

1,300,159.

Specification of Letters Patent.

Patented Apr. 8, 1919.

Application filed June 16, 1917. Serial No. 175,162.

To all whom it may concern:

Be it known that I, JOHN P. GLASHOWER, a citizen of the United States, and a resident of Whitinsville, in the county of Worcester 5 and Commonwealth of Massachusetts, have invented certain new and useful Improvements in Lap-Machines, of which the following is a full, true, and concise specification.

The invention is an improvement in lap 10 machines for winding cotton into rolls for use on combing or other machines, and the object of the improvement is to provide more efficient means for holding the spool while being wound and also ready means for doffing 15 the same when required.

The invention is applicable to existing machines without rearrangement of parts, and is herein shown as applied to an ordinary cotton lap head of familiar construction.

20 In the usual construction of lap heads the lap spool is held in operative position on the winding drums by means of a spindle loosely passing through the spool and screwed into the hub of the lap guiding disk. When it is 25 desired to remove the spool for doffing, or otherwise, the operative unscrews the spindle and then withdraws it from its position inside of the spool, this operation necessitates considerable exertion on the part of the 30 operative as it frequently happens that the parts become locked together rendering it very difficult to separate them. My invention eliminates this difficulty.

With the above object in view, my invention 35 consists of the novel features of construction and the combination of parts hereinafter fully described and claimed, and illustrated in the accompanying drawings, in which:—

40 Figure 1 is a front elevation of the sliver lap machine with my improvements applied thereto; Fig. 2 is a side elevation of the same; Fig. 3 is a partial sectional view of the lap spool holding and doffing means showing 45 the same in doffing position; Fig. 4 is a perspective view of one of the doffing levers showing means for locking the doffing levers while the lap is being doffed; Fig. 5 is an enlarged sectional view of the locking means; 50 and Fig. 6 is a view of a lap guiding disk showing keyways which act in conjunction with means for locking the disk to the spool.

The type of machine illustrated in the drawings is of well known construction, the 55 sliver being wound on the removable spool

1 by the winding drums 2, compression being imparted to the sliver while being wound on the spool by the brake 3 acting on the sliding bearings 4 through the pulley 5, pinions 6 and racks 7, in manner well known. 60

The spool is held between lap guiding disks 8 and 9 provided with hollow sleeves 10 which serve as journals for the disks to rotate on in the bearings 4. In each head of the spool is fastened a bushing 11 bored to 65 form bearings 12 for the doffing spindles 13 which are of short length, slidably mounted within the disk sleeves. Each spindle is provided with a key 14 in sliding relation with the keyways 15 and 16 in the disk sleeve and 70 spool bushing respectively. Normally the spindles are held in a locking relation with the disks and spool due to the compression springs 17 exerting pressure between the shoulder 18 on the spindle and collar 19 fastened to the bearing 4.

In the operation of doffing or releasing the spool the spindles 13 are simultaneously withdrawn from engagement with the spool bushings 12 by means of the manually operated lever 20 acting in conjunction with the doffing levers 21 and 22 fulcrumed on studs 23 and 24 respectively, said studs being in a fixed relation to the top of the sliding bearings 4. The lower ends of the 80 doffing levers are formed with yokes 25 which embrace grooves 26 in the heads of the doffing spindles 13. The arms of the yokes are provided with oppositely located pins 27 which engage with the shoulders of 85 the grooves 26 whereby any motion imparted to the doffing levers is transmitted to the doffing spindles. The upper part of the doffing levers are of such length as to cross 90 each other at the center of the machine forming in the normal position of the levers a V-shaped pocket 28 for contact with the hand lever 20. The upper part of the doffing lever 22 is fork shaped, within the tines 95 of which the upper end of the other doffing lever is confined. When the doffing levers are depressed for the purpose of doffing a lap, a lock is provided to hold the levers in the depressed position thereby allowing the 100 operative the free use of both hands for removing the full lap and replacing with an empty spool. A specific form of this locking means is shown in Figs. 4 and 5. It 105 consists of a spring actuated pin 29 slidably mounted in the boss 30 located on the 110

side of the fork of doffing lever 22. When the doffing levers are depressed to full extent the pin 29 slides into an opening 31 in end of doffing lever 21 thus locking the levers from further movement, until the pin is withdrawn from connection by the operative.

The hand lever 20 is fixed to the shaft 32 in swinging relation to its supporting stands 33 fixed on top of the sliding bearings 4. Normally the lever is held out of contact with the doffing levers by the counterbalance arm 34. When it is desired to doff the lap the operative swings the lever 20 in contact with the doffing levers at their intersection 28, presses down thereon until the doffing levers are in position shown in dotted lines in Fig. 1; this operation withdraws the spindles 13 thus releasing the lap spool so that it may be readily removed.

I do not limit myself to the details of construction here shown, as the same may be variously modified without departing from the spirit of my invention.

Having thus explained the nature of the invention and described a way of construc-

tion and using the same, although without attempting to set forth all of the forms in which it may be made, I declare that what I claim is—

In a lap machine, the combination of two winding drums, of a removable lap spool in frictional contact with the drums, a bushing provided with a keyway fixed in each end of the lap spool, lap guiding disks provided with hollow sleeves having keyways therein, spool holding spindles slidably mounted in the disk sleeves and spool bushings, a key fitted in each spindle, a spring acting on each spindle thereby normally locking them in engagement with the spool, a doffing lever actuating each spindle, a manually operated lever for exerting pressure at the intersection of said doffing levers thereby simultaneously releasing the spindles from the spool, and locking means for the doffing levers comprising a spring operated detent located in one lever and acting in conjunction with a hole in the other lever.

In testimony whereof, I have signed this specification.

JOHN P. GLASHOWER.
